(57) **CLAIM**

The ornamental design for handheld ultraviolet (UV) emission device, as shown and described.

DESCRIPTION

FIG. 1 is a perspective view of the handheld UV emission device;

FIG. 2 is a right side view of the handheld UV emission device in FIG. 1;

FIG. 3 is a left side view of the handheld UV emission device in FIG. 1;

FIG. 4 is a top view of the handheld UV emission device in FIG. 1;

FIG. 5 is a bottom view of the handheld UV emission device in FIG. 1

FIG. 6 is a front view of the handheld UV emission device in FIG. 1; and,

FIG. 7 is a back view of the handheld UV emission device in FIG. 1.

Any broken lines shown are for illustrative purposes only and form no part of the claimed design.
